UNITED STATES PATENT OFFICE

FRANK L. DECKER, OF MAYWOOD, ILLINOIS

FOOTLIGHT STRUCTURE

Application filed May 7, 1928. Serial No. 275,657.

Heretofore, in the construction of footlight structures it has been the practice to build said structures of sheet metal with some form of hood or baffle to keep the light from reflecting into the audience, with the result, that in a short length of time due to the weakness of the sheet metal the structures soon became bent out of shape and presented a battered and unsightly appearance. To obviate some of the above features this invention has been devised to provide a cast-iron or steel housing for use in connection with a footlight structure, said housing being provided with an ordinary tread plate which may be easily walked upon without fear of bending or getting out of shape, and furthermore, provides a protection for the lamps as well as a baffle so that the light will not be projected to points in front of the footlights. The tread plate arrangement also provides a suitable means whereby it is possible to have access to the interior of the wiring chamber to facilitate making repairs or changes in the wiring system.

It is an object of this invention to provide an improved footlight structure equipped with a tread plate and having the lamp sockets thereof arranged at an angle to permit lamps having a maximum end on candle-power to be mounted with or without reflectors and color mediums.

It is also an object of this invention to provide an improved footlight structure having the lamp socket supporting plate positioned at a predetermined angle to permit maximum end on candle-power lamps to be used with the filaments of the top lamps positioned above the top plane of the floor.

It is a further object of this invention to provide an improved footlight structure with a top tread plate adapted to be walked upon if necessary, and furthermore, serving as a protecting means to obviate mechanical injury to the lamps within the structure.

It is furthermore an object of this invention to provide a footlight structure with a protecting tread plate which may be removed to permit easy access to the wire con-

taining chamber to facilitate making repairs or changes in the wiring system.

It is an important object of this invention to provide an improved footlight structure having a removable tread plate and suitable mountings for lamp sockets positioned at predetermined angles to permit a plurality of rows of white and colored lamps to be used with said lamps arranged with the colors in line or with the colors in staggered relation to obtain an even spread of illumination together with the necessary ventilation.

Other and further important objects of this invention will be apparent from the disclosures in the specification and the accompanying drawings.

This invention (in a preferred form) is illustrated in the drawings and hereinafter more fully described.

On the drawings:

Figure 1, is a transverse vertical section through an improved stage footlight structure embodying the principles of this invention.

Figure 2, is a fragmentary vertical section of the footlight structure taken on line II-II of Figure 1.

Figure 3, is a vertical section taken on line III-III of Figure 1.

Figure 4, is a transverse section taken through a modified form of footlight structure using individual type reflectors.

As shown on the drawings:

The reference numeral 1 indicates a stage with the level of said stage indicated by the reference numeral 2.

The front part of the stage is built or provided with a trough or recess 3 formed by means of an inclined wall 4, and a horizontal wall or floor portion 5 at the outer or deepest portion thereof. A suitable nosing 5^a is provided around the front edge of the stage. Mounted in the trough 3 upon the horizontal floor portion 5 is a sheet metal angle casing section 6 the upright flange of which is positioned toward the front of the stage directly behind the nosing 5^a. Mounted within the base casing section 6 are a plurality of spaced reinforcing brack-

ets 7 the upper arms of which are connected by means of an angle bar 8. The upper arms of the brackets 7, together with the angle bar 8, afford a suitable support upon which a non-slip floor or tread plate 9 is adapted to be positioned with the front edge of the tread plate abutting against the back upper edge of the nosing 5^a as clearly illustrated in Figure 1. The tread plate 9 may be constructed of cast-iron or steel, or other suitable material, and is of sufficient strength to permit the same to be walked upon without danger of damaging the same. The tread plate furthermore, affords a guard or protecting plate for the equipment mounted within the footlight structure casing or housing.

Also mounted within the stage trough 3 is a metal front casing section provided with a lower horizontal flanged portion 10 the flange of which is adapted to be secured by screws or other suitable means to the ends of the lower arms of the brackets 7. The front casing section also consists of an irregular front closure plate 11 the upper margin of which is secured by screws or other suitable means to the vertical flange of the angle bar 8.

The front closure plate 11, is provided with two inclined strips or sections 12, having suitable openings therein to afford access to lamp sockets 13 mounted within a wiring chamber 14 formed within the footlight structure casing or housing between the casing sections 6 and 11 and below the tread plate 9. The wiring chamber 14 is adapted to afford a suitable enclosure for the wiring system of the footlight structure and said chamber is readily accessible by removing the tread plate 9 so that changes and repairs may be made to the wiring system within the chamber 14 when necessary. Maximum end on candle-power electric lamps 15 are adapted to be mounted in the lamp sockets 13 at an inclined position as clearly shown in Figure 1 below the overhanging portion of the removable tread plate 9. The lamps 15 in the upper horizontal row project above the floor line 2 of the stage a slight distance so that the greater portion of the filaments of said upper lamps are positioned above the stage floor line.

The arrangement afforded by the improved footlight structure permits the front closure section 11, of the casing or housing which supports the lamps to be readily removed from the trough 3 without necessitating removal of the top tread plate or disarranging the structure in general. The improved footlight structure illustrated in Figures 1 to 3, inclusive, furthermore permits the insertion of color mediums in front of the lamps if desired.

As clearly illustrated in Figure 1 the upper row of white lamps 15 is positioned at a

predetermined angle with a portion of the bulbs projecting above the level of the stage floor and with the center of the source of light of said bulbs being positioned in the plane or slightly above the plane of the stage floor. This arrangement permits the rays emanating from the lamps to produce a more even spread for direct illumination on the stage so that the maximum lighting efficiency is obtainable. If desired the lower row of lamps may be arranged in groups of different colors. A further possibility afforded by the improved footlight structure is the possible arrangement of the lamps in the two rows with the white and colored lamps positioned in staggered relation.

Figure 4 illustrates a modified form of an improved footlight structure wherein a stage 16 is provided with a trough 17 having mounted therein a metal casing or housing 18 affording a wiring chamber 19. One wall 20 of the casing 18 is inclined and has a plurality of lamp sockets 21 mounted on the back thereof in a row so that the wiring for said lamp sockets may be positioned within the wiring chamber 19.

The casing 18 consists of two interfitting sections the one including the inclined wall 20, having mounted on the outer face thereof a plurality of spaced brackets 22. The upper arms of the brackets 22 and the top of the casing 18 afford a suitable support for mounting a metal non-slip tread plate 23 in position. Secured upon the bottom of the tread plate 23 is a longitudinally disposed angle bar 24 which is adapted to abut against the outer ends of the upper arms of the brackets 22. The tread plate 23 is of sufficient strength to permit the same to be walked upon without being injured, and furthermore, serves as a protection or guard for a row of lamp reflectors 25 which are mounted in an inclined position upon the inclined plate 20 of the casing 18. Each of the reflectors 25 has a maximum end on candle-power lamp 26 positioned therein, and supported in the respective socket connected with said reflector. Engaged in the outer end of each reflector 25 is a colored lens 27. The lenses 27 may be white or colored as desired.

While reflectors for holding lenses are shown and described in connection with the single row type of footlight structure illustrated in Figure 4, it will, of course, be understood that lenses carrying reflectors may also be associated in the multiple row arrangement illustrated in Figures 1 and 2. The arrangement shown in Figure 1 may also be adapted for using one row of lamps with reflectors and the other row without, if such an arrangement should be desired.

I am aware that many changes may be made, and numerous details of construction may be varied through a wide range

without departing from the principles of this invention, and I therefore, do not purpose limiting the patent granted hereon, otherwise than necessitated by the scope of the appended claims.

5 I claim as my invention:

1. A footlight structure including a housing, lamp sockets supported therein in an inclined position, a tread plate removably mounted upon the top of said housing, and lamps supported in said sockets at a predetermined angle with the center of the source of light of said lamps positioned substantially in the plane of the top surface 15 of the stage.

10 2. A footlight structure including a sectional housing, brackets supported therein, a tread plate mounted upon said brackets, lamp sockets mounted in a portion of said housing, and lamps engaged in said sockets.

15 3. The combination with a stage and the footlight trough thereof, of a sectional housing mounted in said trough and projecting thereabouts, a plurality of lamp sockets mounted in said housing at a predetermined angle with respect to the level of the stage, electric lamps supported in said sockets on the exterior of said housing and projecting above the level of the stage with the 20 center of the source of light of said lamps substantially positioned in the plane of said stage, and a tread plate removably supported on the top of said sectional housing and projecting over said lamps to afford a shield 25 therefor.

4. In combination, a stage and the footlight trough thereof, a housing mounted in said trough and having a wiring chamber therein accessible through the top of said housing, means for supporting lamps on a portion of said housing in an inclined position, and a tread plate mounted on the top of said housing to close the wiring chamber, and furthermore serving as a protection for 40 said lamps.

45 5. The combination with a stage and the footlight trough thereof, of a sectional housing mounted within said trough and affording a wiring chamber, brackets mounted in said housing, an angle bar secured to said brackets, lamp sockets mounted on the interior of said housing and accessible from the exterior of said housing, lamps mounted in said sockets and projecting into the foot- 50 light trough, and a tread plate supported on said brackets and on said angle bar to close said wiring chamber and project over said lamps to afford a shield therefor.

6. The combination with a stage and the 55 footlight trough thereof, of a housing seated in said trough and comprising a base section and a front section, brackets mounted within said base section, lamp sockets mounted on said front section, lamps supported in said sockets and projecting into

said trough, and a tread plate supported on said brackets to close said housing and overhang said lamps to protect the same.

7. The combination with a stage and the footlight trough thereof, of a housing seated in said trough, lamp sockets secured to said housing adapted to support the lamps on the exterior of said housing, brackets secured to said housing, and a tread plate supported on said housing and brackets in overhanging relation with respect to said lamps. 70 75

8. The combination with a stage and the footlight trough thereof, of a sectional housing seated in said trough, a tread plate supported on said housing and partially projecting over said trough, lamp sockets supported on said housing, lamps engaged in said sockets and projecting beneath the overhanging portion of said tread plate, reflectors for said lamps, and lenses supported 80 85 in said reflectors to enclose the lamps.

9. The combination with a stage and the footlight trough thereof, of a housing within said trough, brackets mounted on said housing, a tread plate supported on said housing and on said brackets, lamp sockets within said housing, lamps engaged in said sockets on the exterior of said housing, and reflector means supported on said housing 90 95 to enclose said lamps.

10. In combination, a footlight structure including a housing and a plurality of lamps therein, and a tread plate overhanging said lamps and usable while said lamps are operating. 100

11. In combination, a footlight structure including a housing and a plurality of lamp sockets therein, and a tread plate projecting over said sockets and the lamps which may be associated therewith, said tread plate being usable at all times. 105

12. In a footlight structure, a sectional housing defining a wiring chamber and having lamp sockets associated therewith, and a tread plate projecting over the upper portion of said housing, the front wall of said housing being removable with said tread plate in useful position. 110 115

In testimony whereof I have hereunto subscribed my name.

FRANK L. DECKER.
